WASHING MACHINE.

Application filed June 1, 1925. Serial No. 34,009.

This invention relates to a washing machine and particularly to a simple and efficient operating mechanism for a washing machine having a movable or reciprocated member in a closed receptacle adapted to engage the clothes.

It is an object of this invention to provide a washing machine comprising a receptacle for containing clothes and liquid, a plurality of movable members adapted to engage the clothes and an operating mechanism connected to said reciprocating members comprising yieldable means adapted to yield when excessive resistance is encountered by said reciprocating member.

It is a further object of the invention to provide a washing machine comprising a frame carrying adjacent its top a receptacle adapted to contain the clothing and liquid, a plurality of reciprocating members adapted to engage the clothes and extend through a cover on said receptacle, together with operating mechanism connected to said reciprocating members and disposed above said cover and which comprises an oscillating beam, a crank shaft disposed above said receptacle to which said beam is connected, said connection comprising yielding members adapted to yield when excessive resistance is encountered by said reciprocating members in said receptacle.

It is also an object of the invention to provide such a washing machine as set forth in the preceding paragraph in which said crank shaft is driven by a shaft extending at one side of the receptacle and downwardly to a motor shaft driven by a motor disposed beneath said receptacle.

Other objects and advantages of the invention are to provide a simple and efficient yielding operating mechanism for the reciprocating members in the liquid and clothes receptacle and to provide a simple and efficient driving mechanism for said operating mechanism and also for a wringer.

These and other objects and advantages of the invention will be fully set forth in the following description made in connection with the accompanying drawings in which like reference characters refer to the same parts throughout the different views, and in which,

Fig. 1 is a view in side elevation of the machine, certain parts thereof being shown in vertical section;

Fig. 2 is a top plan view of the machine, one casing portion thereof being shown in horizontal section;

Fig. 3 is a view of a motor and driving means connected thereto partly in side elevation and partly in vertical section, taken on the line 3—3 of Fig. 1;

Fig. 4 is a view in side elevation of a portion of the operating mechanism;

Fig. 5 is a section taken on the line 5—5 of Fig. 4, as indicated by the arrows;

Fig. 6 is a vertical section taken on the line 6—6 of Fig. 2, as indicated by the arrows; and

Fig. 7 is a vertical section taken on the line 7—7 of Fig. 2.

Referring to the drawings, the machine comprises a frame having corner members 10 arranged at the corners of a rectangle. While the members 10 may be of various shapes, in the embodiment of the invention illustrated, they are shown as formed of angle irons with corners thereof disposed outwardly. The members 10 are connected at intermediate points thereon by four members 11 which are also illustrated as made of angle irons having their corners disposed outwardly and one side thereof vertical and one side horizontal. The members 11 form the support for a rectangular receptacle 9 disposed within the vertical sides thereof and within the sides of the members 10, said receptacle having an outwardly directed flange at its top extending over angle irons 12 also extending between the angle irons 10 adjacent the upper ends of the latter, said angle irons 10 having one side thereof bent outwardly and secured beneath the horizontal sides of the members 12, as clearly shown in Fig. 7. Suitable tie or brace members 11^a are connected to the members 10 and 11 adjacent their junction point, as shown in Fig. 1. A top frame is provided consisting of four angle bars 14 having one horizontal side directed inwardly and one side directed vertically, said bars being arranged in a rectangle in alignment with the frame of the machine already described and being joined at the corners by angle braces 15 and flat braces 16 and 16^a. A pair of angle bars 17 extend between opposite ones of the bars 14, said bars 17 having one of their sides bent inwardly and riveted to bars 14, said rivets, at one side of said frame which will be referred to as the front side,

also extending through attaching flanges on a bail handle 18. The frame comprising members 14 and 17 is mounted for upward swinging movement and at its end the brace members 16 are extended through the vertical flange of the members 14 at the side opposite the handle 18 and bent downward, as shown at 16^b, the lower ends of the same being bent around pivot members 20 carried in brackets 21 riveted to the outer side of members 10 at the rear of the frame. The portions 16^b are further strengthened by brace members 16^c riveted to their outer sides adjacent the hinge pins 20 and secured at their upper sides to the vertical web of members 14 at the sides of the frame. The frame comprising members 14 and 17 has secured thereto beneath said members a sheet metal top 22 which fits down in flat contact with the outwardly directed flange at the top of receptacle 9. The frame 14 with the cover 22 and parts carried thereby is limited in its swinging movement and in its open position by a pair of links 13 disposed at each side of the frame, the links of each pair being pivotally connected together at one end and having their other ends respectively pivoted to one of the side bars 14 and to a lug 12^a secured beneath the horizontal flange of one of the bars 12. One of the links 13 is projected beyond the pivot connecting the same with the other link and has a pin 13^a extending transversely therethrough and projecting at one side thereof adapted to contact with the side of the other link 13 to limit the opening movement of the frame and cover.

The members 10, at the front of the machine, each have secured thereto adjacent their tops small channel brackets 43 and latch members 44 are pivoted between the sides of these brackets by a suitable pivot shown as a headed rivet. The lower ends of the latches 44 have a pin projecting toward the members 10, which pin is embraced by one end of a small coil compression spring 45, the other end of which surrounds the end of one of the attaching bolts or rivets of the bracket 43. The upper end of the latch 44 is formed as a pointed block or keeper and is adapted to pass through an opening 14^b in the vertical web of one of the side channel bars 14 so as to engage the horizontal side of said bar. The hook has a cam action on the bar and thus tightly holds the same down on the bar 12. The rod 46 extends across the front of the machine being journaled at its ends in the brackets 43, which rod has secured thereto in front of each of the members 44 below the pivots thereof, a lug 47. The rod 46 is provided with a handle 48. When said rod is oscillated by handle 48 the dogs 47 will push inward on the lower ends of ratchet 44 and release said latches.

The cover 22 is provided with holes through which extend spaced rods 24 carrying at their lower ends hollow funnels 25 made of sheet metal and having their lower ends open to form cups. The rods 24, at 70 their upper ends, are secured in tubular members 26 which members 26 are bifurcated at their top to receive between their sides the hubs or bosses at each end of a beam 27. As shown in Figs. 1 and 2, there are two of such beams 27 and there are thus four of the cups 25. The members 26 connected to each beam 27 are pivotally connected to bars 26^a, which bars have U-shaped ends embracing members 26 and are also centrally pivoted at 26^b to cross bars 30^a of brackets 30. As shown in Fig. 6, the beams 27 are journaled on sleeves 28, which sleeves are, in turn, journaled on a shaft 29, which shaft is mounted in and extends between brackets 30 rising from and secured to the members 17. The mechanism for operating each of the beams 27 is the same and only one of said mechanisms need be described. An arm 31 has a hub at its upper end embracing and secured to the sleeve 28. While this arm may be secured in any manner, in the embodiment of the invention illustrated the same is shown as being secured to sleeve 28 by a set screw. The sleeve 28 has a collar 28^a adjacent one end and abuts at one end adjacent the bracket 30. A collar 32 secured to shaft 29 abuts the other end of sleeve 28 and holds the same in position, the collar 32 being shown as held in place by a suitable set screw. The arm 31 depends from sleeve 28 and shaft 29 and has a boss adjacent its lower end through which extends a headed and nutted pivot bolt 33 pivotally connected to said arm and to one end of a link 34. Below the pivot 33 arm 31 has a block 31^a formed thereon having bores extending therethrough at an angle to each other, shown as slightly less than a right angle, through which bores extend rods 35 and 36, said rods being threaded at their ends below the block 31 and provided with nuts which contact the lower faces of block 31^a. Said rods 35 and 36 are loosely fitted in the block 31^a 110 to be slidable therethrough and above the block 31^a members 37 are disposed having bores through which rods 35 and 36, respectively slidably extend, said members 37 having projections at their lower sides of semi-cylindrical formation contacting the upper surface of block 31^a. Coiled compression springs 38 surround rods 35 and 36 and abut against the flat upper surface of members 37 at their lower ends and at their upper ends abut against oblong plates 38^a, which plates 38^a, at their upper sides, are disposed flat against the undersurfaces of flat plate-like members 39 which latter members have a pair of ears 39^a embracing the beam 27 130

adjacent its ends and connected thereto by a suitable pivot. The members 27 extend at each side of the rods 35 and 36 and have threaded thereinto the lower ends of a pair 5 of bolts or headed rods 40, which rods 40 are parallel respectively, to the rods 35 and 36 and at their upper ends extend slidably through members 38^a and 39 and have their heads in engagement with the upper surface 10 of members 39.

There are, as shown, a pair of the links 34 and these links extend toward the rear side of the frame and are connected by suitable cap bearings to the crank pins of 15 cranks 41^a on a crank shaft 41, which crank shaft is journaled in bearings 42 secured to the bars 17 and one of the side bars 14, said crank shaft extending through and at one side of said bar 14.

20 The shaft 41 has a beveled gear 50 at its outer end meshing with a beveled gear 51, which gears are disposed in a suitable casing 52 secured to one of the members 14, which casing has a downwardly inclined hub 53 25 forming a bearing for the shaft 54 which carries the beveled gear 51, said shaft being held in place by a collar 55 pinned thereto below the hub 53. The shaft 54 carries a toothed half clutch 56 adapted to engage, 30 when the cover is in closed position, with another half clutch 57 splined to the upper end of a shaft 58, which shaft has a collar 59 secured thereto some distance below the half clutch 57 between which and the half clutch 35 57 a coiled compression spring 60 is disposed.

The collar 59 revolves in a tubular casing 61 through which shaft 58 extends, said shaft being journaled at its lower end in bearings provided in a gear casing 62. The 40 casing 61 extends to a point beyond the half clutch 57 and at its lower end fits over a projection on the top cover 62^b of casing 62. Shaft 58, adjacent its lower end, has secured thereto a worm wheel gear 66 45 driven by a worm gear 67 secured to a motor shaft 68 driven by a suitable motor 69 mounted on a platform 11^b formed by angle bars extending between the members 10 adjacent their lower ends, the casing 62 50 being secured to a shelf or smaller platform 11^c formed by angle bars secured to bars 11^b and 10. Said casing also has a flange 62^a secured to one of the members 10, as well as a lower cover plate 62^c forming 55 a bearing for the terminal of shaft 58. The shaft 58 has a beveled gear 70 at its lower end meshing with the gear 71 secured to the lower end of a shaft 72 journaled in a bearing formed in casing 60 62 and extending upwardly through a tube 73, said shaft 72, at its upper end, being adapted to receive driving means for a wringer which will be disposed in a cylindrical casing 74 at the upper end of tube 65 73 secured by a strap bracket 75 to the

member 10. A spring-pressed pivot pawl lever 76 is shown in Fig. 2 having a handle thereon, which lever has teeth 76^a adapted to mesh with teeth on the wringer standard (not shown) to hold the same in various 70 circumferential positions.

The cover 22 is provided with a glass window 22^a therein and the frame members 10 preferably are equipped with suitable casters and caster brackets 77 at their lower ends. 75 A switch casing 79 is secured to the front of the machine which will have suitable switches for controlling the motor 69. Part of the operating mechanism for the cups 25 which is carried above the receptacle, is preferably 80 inclosed in a casing 78 shown in Fig. 2.

In operation, the handle 48 will be operated to release the latch members 44 and the frame comprising members 14 and cover 22 will then be lifted by handle 18. When this 85 frame is lifted it carries with it the cup members 25 and all of the operating mechanism carried on the frame comprising members 14 and 17 and half clutch 56 secured to shaft 54 and to said frame, the cover swinging back until the pin 13^a on one of the links 13 engages the other link 13. The washing liquid and materials and the clothes can now be placed in the receptacle 9 after which the lid will again be moved to closed position 90 and the latches 44 engaged. It will be noted that if the teeth on the half clutches 56 and 57 are not in meshing position, the half clutch 57 will merely be depressed against the tension of spring 60 until relative rotation occurs between said half clutches, at 95 which time the teeth will mesh. The motor is now started by closing the proper switch in the switch casing 79 and shafts 72 and 58 will be driven through the gearing in casing 100 62. Shaft 54 will be driven through the half clutches 56 and 57 and crank shaft 41 will thus be rotated through the gears 51 and 52. The cranks 41^a on crank shaft 41, it will be noted, are quartered or spaced ninety degrees 105 apart. The links 34 will be reciprocated and arms 31 oscillated. As arm 31 is oscillated, the block 31^a at the bottom thereof will alternately push upwards on the members 37 and springs 38 against the ends of beams 27. The 110 beams will thus be oscillated about the axis of shaft 29 and on the sleeves 28 and the cups 25 carried at the respective ends of said beams will be reciprocated in the receptacle 9 and will be pressed down upon and lifted 115 from the clothes. Bars 26^a cause members 24 and 25 to reciprocate substantially vertically. A pressing or pounding and a suction action will thus be effected and the clothes in the water will be thoroughly agitated and cleaned. The springs 38 are of sufficient tension to give the necessary reciprocation to the cups 25 under normal conditions. If, however, an excessive resistance 120 should be encountered by the descending cup

125

25 the spring 38 would be compressed and the block 31^a on its respective arm would move relatively to its rod 35 or 36. The lower end of said rod 35 or 36, as the case 5 may be, will project at the lower face of block 31^a and the rods 40 will be projected slightly through the members 39. When the cup encountering the resistance will again be lifted the springs 38 will expand and the 10 parts will take their normal position with the nut at the lower end of rod 35 or 36 in engagement with the block 31^a and the heads at the top of rods 40 in engagement with the members 39. The springs 38 thus form a 15 yieldable means for the operating mechanism adapted to yield under excessive stress and prevent injury to any of the parts. By the disposition of the cranks 41^a the load at the sides of the machine is nicely balanced and 20 there is practically no vibration due to the reciprocation of the cups 25. The cover 22, preferably is formed somewhat convex on its underside, as shown in Fig. 1, so that the liquid thereon will drain to the center and 25 drop into the receptacle. The operation of the cups 25 can be observed, when desired, through the window 22^a.

From the above description it is seen that 30 applicants have provided a simple and efficient washing machine and one having an efficient and yet very safe operating mechanism for the operating parts. The machine is very convenient in operation and the same has been amply demonstrated in actual practice 35 and found to be very successful and efficient.

It will, of course, be understood, that various changes may be made in the form, details, arrangement and proportions of the 40 parts without departing from the scope of applicants' invention, which, generally stated, consists in a device capable of carrying out the objects above set forth, in the novel parts and combination of parts disclosed and defined in the appended claims.

45 What is claimed is:

1. An actuating mechanism for the reciprocating elements of a washing machine comprising an operating shaft, a reciprocating member connected to said shaft, a beam 50 movable about a stationary axis and to which said elements are connected and a yieldable connection between said reciprocating member and each end of said beam, whereby under normal resistance to said elements said beam will be moved with said reciprocating member, but under excessive resistance to 55 said elements said yielding connection will yield and said reciprocating member will move relatively to said beam.

60 2. An actuating mechanism for the reciprocating elements of a washing machine, comprising a crank shaft, a link connected to said crank shaft, a second shaft, a sleeve journaled on said second shaft, an arm secured to said 65 sleeve and connected to said

link to be oscillated thereby, a beam journaled on said sleeve to the ends of which said reciprocating elements are connected, and a yieldable connection between said arm and each end of said beam whereby under normal resistance to said reciprocating elements, said yieldable connection will yield and said arm will move relatively to said beam. 70

3. An actuating mechanism for the reciprocating elements of a washing machine 75 comprising spaced brackets, a stationary shaft carried in said brackets, a crank shaft extending parallel to said stationary shaft at one side thereof, a sleeve journaled on said stationary shaft, an arm secured to said sleeve and depending therefrom, a link connected to a crank on said crank shaft and pivotally connected to said arm adjacent the lower end thereof, a beam journaled on said sleeve to the ends of which said reciprocating elements are pivotally connected, a pair of rods extending through the lower end of said arm, members pivotally connected adjacent each end of said beam, the upper ends 80 of said rods being slidably connected respectively to said respective members, a spring surrounding each of said rods and re-acting between said respective members and the lower end of said arm and means for operating said crank shaft whereby under 85 normal resistance to said reciprocating elements said springs will yield and said arms will move relatively to said beams. 90

4. An actuating mechanism for the reciprocating elements of a washing machine, comprising an oscillating beam pivoted at its center and connected at its ends to said reciprocating elements, an oscillating arm, a member carried by said arm having a pair of rods slidably therethrough, said rods being angularly disposed and extending from said member to adjacent the ends of said beam, members pivoted adjacent the ends of said beam to which the upper ends of said rods are secured, compression springs surrounding said rods abutting the member on said arm at their lower ends and abutting said last mentioned members at their upper ends. 100

5. An actuating mechanism for the reciprocating elements of a washing machine comprising an oscillating beam pivoted at its centre and connected at its ends to said reciprocating elements, an oscillating arm having an enlarged portion thereon, a pair of rods slidable through said enlarged portion of said arm, said rods being angularly disposed and extending from said portion to adjacent the ends of said beam, members pivoted adjacent the ends of said beam to which the upper ends of said rods are secured, members through which said rods are adapted to slide engaging the enlarged portion of said arm, springs re-acting between said first mentioned and said last mentioned 115 120 125 130

members and rods disposed at the sides of said first mentioned rods and secured at one end to said last mentioned members, the other ends of said last mentioned rods 5 ably extending through said first mentioned members.

6. An actuating mechanism for the reciprocating elements of a washing machine comprising a beam centrally pivoted and connected at its ends to said reciprocating elements, an operating shaft, a reciprocating member connected at one end to said shaft, means connected to the other end of said reciprocating member and to said beam for 10 oscillating said beam as said operating shaft is moved and a resilient cushioning means interposed between said connecting means and said beam adapted to take up the motion of said reciprocating member as the free 15 movement of said elements becomes obstructed.

7. An actuating mechanism for the recip-

rocating elements of a washing machine having in combination, a frame, a shaft journaled therein, a beam pivoted on said shaft, 25 an arm pivoted on said shaft, means for oscillating said arm, a rod extending through and slidable in said arm, a member engageable by said arm through which said rod is slidable, a pair of rods secured at one end 30 to said member, a block to which the other ends of said last mentioned rods are slidably connected, means pivotally connecting said block to said beam, and a spring surrounding 35 said first mentioned rod and abutting said member and block whereby said beam is oscillated by oscillation of said arm and said spring will be compressed and said rods move relatively to said arm and block if the movement of said beam is arrested. 40

In testimony whereof we affix our signatures.
